CLAIM

We claim the ornamental design for the hand-held electrical device, as shown and described.

DESCRIPTION

FIG. 1 is a perspective view of the hand-held electrical device embodying our new design;

FIG. 2 is a front view thereof;

FIG. 3 is a left side view thereof;

FIG. 4 is a back view thereof;

FIG. 5 is a right side view thereof;

FIG. 6 is a top view thereof;

FIG. 7 is a bottom view thereof;

FIG. 8 is a perspective view of a second embodiment of the hand-held electrical device embodying our new design;

FIG. 9 is a front view thereof;

FIG. 10 is a left side view thereof;

FIG. 11 is a back view thereof;

FIG. 12 is a right side view thereof;

FIG. 13 is a top view thereof; and,

FIG. 14 is a bottom view thereof.

In FIGS. 1–6, the broken lines which connect the outer, solid contour lines and which are immediately adjacent the shading lines represent the bounds of the claim. In FIGS. 1–13, all other remaining broken lines illustrate portions of the article. None of the broken lines forms part of the claimed design.
